United States Patent Office

Des. 183,725
Patented Oct. 21, 1958

183,725

BOWLING GAME APPARATUS

Lyndon A. Durant, Chicago, Ill., assignor to United Manufacturing Company, Chicago, Ill., a corporation of Illinois

Application September 27, 1957, Serial No. 47,902

Term of patent 14 years

(Cl. D34—5)

Fig. 1.

Fig. 4.

Fig. 5.

Fig. 1 is a perspective view of a bowling game apparatus, showing my new design;

Fig. 2 is a side elevational view;

Fig. 3 is an opposite side elevational view;

Fig. 4 is a front elevational view; and

Fig. 5 is a fragmentary top plan view thereof.

A portion of the drawing figures is diagonally lined to indicate transparency.

I claim:

The ornamental design for a bowling game apparatus, substantially as shown and described.
